UNITED STATES PATENT OFFICE

91,866

DESIGN FOR A DISPLAY DEVICE

Joseph Friedman, New York, N. Y.

Application January 5, 1934, Serial No. 50,328

Term of patent 3½ years

To all whom it may concern:

Be it known that I, JOSEPH FRIEDMAN, a citizen of the United States, residing at 11 Waverly Place, in the city and county of New York and State of New York, have invented a new, original, and ornamental Design for a Display Device, of which the following is a specification, reference being had to the accompanying drawing, forming part thereof.

Figure 1 is a view in front elevation of a display device, showing my new design.

Figure 2 is a view in side elevation thereof.

Figure 3 is a top plan view.

I claim:—

The ornamental design for a display device as shown.

JOSEPH FRIEDMAN.
